(57) CLAIM

The ornamental design for a bingo card holder, as shown and described.

DESCRIPTION

FIG. 1 shows a front left perspective view of the bingo card holder showing my new design.

FIG. 2 is a front right perspective view of the bingo card holder.

FIG. 3 is a left side view of the bingo card holder.

FIG. 4 is a right side view of the bingo card holder.

FIG. 5 is another front right perspective view of the bingo card holder; and,

FIG. 6 is a rear perspective view of the bingo card holder. The broken lines in the drawings depict portions of the bingo card holder that form no part of the claimed design.
